UNITED STATES PATENT OFFICE.

HENRY A. THUERNAU, OF CHICAGO, ILLINOIS.

DESIGN FOR AN ADVERTISING SIGN.

Application filed April 6, 1922. Serial No. 1,570. Term of patent 3½ years.

To all whom it may concern:

Be it known that I, HENRY A. THUERNAU, a citizen of the United States, residing at 4837 Kenmore Avenue, Chicago, in the county of Cook and State of Illinois, have invented a new, original, and ornamental Design for an Advertising Sign, of which the following is a specification, reference being had to the accompanying drawings, forming part thereof.

The figure is a perspective view of an advertising sign showing new design.

I claim:

The ornamental design for an advertising sign, as shown.

In testimony whereof, I affix my signature in the presence of two witnesses at 36 West Randolph Street, Chicago, Illinois.

HENRY A. THUERNAU.

Witnesses:

DANIEL A. BRENNAN,
EVELYN PATOUX.
